J. REYNOLDS.
Soft Rubber Apparatus.

No. 15,087.

Patented June 10, 1856.

UNITED STATES PATENT OFFICE.

JAMES REYNOLDS, OF NEW YORK, N. Y.

FEED APPARATUS FOR WORKING GUTTA-PERCHA.

Specification of Letters Patent No. 15,087, dated June 10, 1856.

To all whom it may concern:

Be it known that I, JAMES REYNOLDS, of the city, county, and State of New York, have invented a new and useful Forcing Apparatus for Forcing or Pressing Gutta-Percha into Dies or Molds; and I do hereby declare that the following is a full, clear, and exact description of the same, reference being had to the accompanying drawings, forming part of this specification, in which—

Figures 1 and 2, are vertical sections at right angles to each other of my forcing apparatus.

Similar letters of reference indicate corresponding parts in both figures.

This invention is principally intended to be employed in the manufacture of gutta percha rope and tubing and in covering wire, in which manufactures it is extremely desirable to have a continuous forcing operation to drive the material through the die. The most convenient and it may be said the only practicable way of producing a perfectly continuous and uniform forcing action is by means of a rotary forcing apparatus. Attempts have been previously made to construct a rotary apparatus for this purpose but owing to the peculiar character of the material and its liability to clog the apparatus these attempts have been hitherto unsuccessful.

This invention consists in a rotary apparatus of peculiar construction which operates with the greatest success.

To enable others to make and use my invention, I will proceed to describe its construction and operation.

A, is a box of cast iron or other strong material whose horizontal section is of quadrangular form, open at the top and closed at the bottom but having two holes *a*, *a*, on opposite sides near the bottom to receive the dies for forming the interior and exterior of tubing. On one side of the upper part, is a concave *b*, *b* see Fig. 1, of the form of an arc of a cylinder described from a horizontal axis.

B, is a shaft to which is attached a hollow cylindrical head C, C. This shaft and head are fitted to work in bearings in opposite ends of the box as shown in Fig. 2, said bearings being concentric to the axis from which the arc *b*, *b*, is described. The exterior of the cylindrical head is of such diameter as to work in contact or nearly so with the side *c*, of the box opposite to the concave *b*, *b*,

which leaves a considerable space between it and the concave *a*, *a*. The cylindrical head C, C, contains a number of radial slots of the whole length of the box to receive a corresponding number of straight and parallel sided slides or, as they may be termed, sliding pistons D, D, consisting merely of pieces of metal of a length and thickness to fit and work very easily in the slots and of a depth to reach from the interior of the cylindrical head to the face of the concave *b*, *b*. These slides are merely faced smooth and are without packing.

E, is a stationary shaft which is placed within the cylindrical head C, C, and is firmly secured to one end of the box by means of a screw on its end and a nut *g*, outside the box. This shaft is truly cylindrical on the greater part of its circumference and of a size to fit easily to the interior of the cylindrical head C, C, which is bored truly to receive it but the remainder of its circumference is cut away in such a way that it may allow the sliding pistons to move into the cylindrical head as they are severally brought in contact with the side *c*, of the box by the rotation of the shaft D, and cylindrical head, and that it may serve as a stationary cam to force out the sliding pistons again as they leave the side *c*. The stationary shaft E, has a small hole *d*, bored from the end which protrudes from the box nearly to the other end, and to this hole several small passages *e*, *e*, communicate from the space *f*, which is left between the eccentric portion of the stationary shaft E, and the interior of the cylindrical head. The box A, is intended to be surmounted by an upright tube which is to be kept heated by a steam jacket and to contain a column of gutta percha in a melted or plastic state to keep the box A, constantly supplied.

The operation of the apparatus is as follows: Rotary motion being given to the shaft B, and cylindrical head C, C, in the direction of the arrow shown in Fig. 1, the pistons are severally forced out as they approach their highest position and then descending in contact with the concave force down the material into the lower part of the box thereby producing the necessary pressure to fill the dies; and they are driven again as they come in contact with the side *c*, of the box. As far as the operation is thus described, it does not differ from that of some rotary forcing pumps but there are

- two important novel features in the apparatus in which it differs from all other apparatus known to me, one of which is that the cam for forcing out the pistons is entirely within the rotating head which carries them, which in connection with the other feature of difference which is of still more importance to the perfect operation, prevents the clogging of the machine.
- 10 The other and more important feature of novelty consists in the passages *e*, *e*, *d*, by which any material leaking past the pistons into the space *f*, is allowed to escape through the shaft *E*. Without this provision for escape or leakage the apparatus would be totally impracticable unless packed sliding pistons were employed as the gutta percha would get into and fill the space *f*, and thus stop the operation of the pistons, and with 15 packed pistons the apparatus would operate very stiffly and require enormous power to drive it. But by fitting the pistons easily and providing for leakage in this way the

gutta percha is made to serve as lubricating material to the pistons and enables the machine to work easily, while the escape is quite inconsiderable and causes no waste as the escaping material is all collected and worked again. Thus the construction of the machine is reduced to the highest degree of simplicity 20 and yet its operation is perfect.

What I claim as my invention, and desire to secure by Letters Patent, is,

The combination of the rotary forcing apparatus, consisting of a cam *E*, for forcing out the sliding pistons *D*, *D*, arranged entirely within the rotating head *C*, *C*, with a passage or passages within the rotating head which carries the said pistons, providing for leakage, substantially as and 30 35 40 for the purposes herein described.

JAMES REYNOLDS.
